UNITED STATES PATENT OFFICE.

DECKER R. BEARDSLEY, OF HUNTSBURG, OHIO.

SAP-BUCKET.

SPECIFICATION forming part of Letters Patent No. 611,229, dated September 27, 1898.

Application filed January 8, 1898. Serial No. 666,004. (No model.)

To all whom it may concern:

Be it known that I, DECKER R. BEARDSLEY, a citizen of the United States, residing at Huntsburg, in the county of Geauga and State of Ohio, have invented certain new and useful Improvements in Sap-Buckets; and I do declare that the following is a full, clear, and exact description of the invention, which will enable others skilled in the art to which it appertains to make and use the same.

My invention relates to sap-buckets; and the object of the invention is to provide a sap-bucket with a cover which is so secured that while it can be tilted to empty the bucket it cannot be blown off or displaced by the wind and will exclude rain, snow, and droppings of every kind from without.

The invention therefore consists of a sap-bucket having a cover adapted to be swung open and shut and which is firmly secured in place when closed, all substantially as shown and described, and particularly pointed out in the claims.

In the accompanying drawings, Figure 1 is a perspective view of my improved sap-bucket and a section of a tree and a sap-spout therein on which the bucket is hung. Fig. 2 is a side elevation of the bucket complete and enlarged as compared with Fig. 1, and Fig. 3 is a plan view thereof. Fig. 4 is a sectional elevation of the bucket turned half-way over as it would be to empty it of sap by swinging it on the sap-spout and showing the lid or cover open as far as it will go for this or any other purpose. Fig. 5 is a perspective view of the bail alone.

In Fig. 1, A represents a section of a tree, and B a sap-spout of any suitable kind and secured so firmly in the tree as to suspend thereon and support a sap-bucket when filled with sap.

C is a sap-bucket, which may be of any common or available kind and of any desired size or pattern and made of any suitable material. As shown, the bucket has a hole 2 near its top, at one side, through which it is suspended on the spout B.

D represents the cover or lid of the bucket, which is designed to have sufficient size to thoroughly cover the bucket over and leave more or less projection about its edge, so as to afford the most perfect protection to the

contents of the bucket and prevent bark from the tree or other loose or flying particles, as well as insects or other foreign and objectionable matter, coming into the accumulating sap. .

But two things especially are deemed important to a perfect cover for a sap-bucket. The first of these is that the cover should be so secured as to be fixed against lifting or lateral displacement when down, thereby preventing possible displacement by wind or the like, and the second essential is that the cover may open sufficiently when the bucket is swung on spout B to empty it of sap without obstructing or interfering with this operation and either automatically swing out of the way or be easily swung or tilted by hand. Then when the bucket drops back to its proper position again the cover should automatically find its place. To these several ends I provide the cover with a bail E, constructed substantially as herein shown. This bail is preferably made of wire, and its center or middle is formed with a tongue 4, projecting back some distance from its body portion 5 and pivotally secured to the cover C, substantially as shown, or in any good mechanical way. The sides 7 of the bail are bent downward at right angles to the parallel cross portions 5 and pass through holes 8 in the cover, where the extremities of the bail are then bent inwardly at right angles, as indicated by 9, Fig. 5, to engage through holes 10 in the top and side of the bucket and thus secure the bail and the cover on the bucket. The bail being of spring-wire a spring engagement is made with the bucket, and the holes 8 are large enough to allow the said extremities of the bail to be sprung outward sufficiently to detach the bail and the cover together from the bucket. One or both ends of the bail may be adaptable in this way, so that the bail may be easily attached or detached but will remain securely in place until removed by hand.

The length of the right-angled portions 7 from the engaging portion 9 to the shoulder 12 indicates the limit of movement outward of the cover C, as seen in Fig. 4, and about the same limit occurs if the cover be swung in the opposite direction, as seen in dotted lines, Fig. 4. It will also be seen that when

the cover is down and the bucket in its hanging position it is impossible to displace the cover laterally in any direction and that it cannot be thrown into inclined position until

5 it is raised to the shoulders 12; but even then the bucket continues to be sheltered from above, and unless the cover be held by hand in inclined position it will automatically resume its place. In fact, the invention provides what may be called a "perfect" cover for sap-buckets and one which is attached or detached, as may be desired.

What I claim is—

1. In sap-buckets, a cover having a bail with side portions passing through the cover and having a central tongue pivotally connected with the cover, substantially as described.

2. A sap-bucket and a cover therefor, and a bail to secure the cover on the bucket having

shouldered side portions extending through the edge of the cover and its extremities engaging the bail to the bucket, substantially as described.

3. The bucket and the cover therefor, in combination with the bail provided with a tongue at its middle pivotally connected with the cover and having vertical side portions passing through the cover and engaged with the bucket at their lower ends and shoulders at the tops of said side portions limiting the upward movement of the cover, substantially as described.

Witness my hand to the foregoing specification this 31st day of December, 1897.

DECKER R. BEARDSLEY.
